ORNAMENT FOR AN AUTOMOBILE HOOD

Marshall M. Fredericks, Birmingham, Mich., assignor to Studebaker-Packard Corporation, a corporation of Michigan

Application November 3, 1954, Serial No. 32,947

Term of patent 14 years

(Cl. D14—18)

FIG. 2

FIG. 3

FIG. 4

Figure 1 is a front quarter view in perspective showing my new design of an ornament for an automobile hood.

Figures 2, 3, and 4 are, respectively, top plan front elevation and side elevation views of the ornament of Figure 1, and

Figures 5 and 6 are sectional showings taken along the sectional lines 5—5 and 6—6, respectively, in Figure 2.

The characteristic features of my design reside in the portion shown by means of full lines in the drawing.

What is claimed is:

The ornamental design for an ornament for an automobile hood, as shown.
